UNITED STATES PATENT OFFICE.

WILLIAM T. SCOTT, OF YOUNGSTOWN, OHIO.

TOOL FOR SEPARATING ADHERING SHEETS.

Application filed June 26, 1926. Serial No. 118,706.

In the manufacture of metallic sheets and more particularly those made of ferrous material it is customary to anneal the sheets or perform certain other operations upon them when the sheets are arranged in piles or packs and it frequently happens as a result of these operations that the individual sheets adhere or stick to each other so that they have to be forcibly separated. This condition most frequently arises when the pack of sheets is overheated during the annealing process but whatever be the particular cause thereof the subsequent separation of the sheets must be effected in such manner and by such means as will prevent damage to the sheets and particularly to their surface finish.

It is therefore an object of my invention to provide an improved tool for separating the sheets in a pack or pile of sheets which have adhered to each other which is of such character and which may be so operated as to effect the requisite separation without damaging the sheets.

A further object of the invention is to provide a tool adapted for the performance of the aforesaid function which embodies a separating head of peculiar formation and means for forcing the head between the adhering sheets by imparting to it a series of blows or impulses delivered in rapid sequence and which also embodies novel means for maintaining the head in operative relation with the other parts of the device.

Still further objects of the invention are to provide an improved tool for separating sheets which is of relatively simple construction and not liable to get out of order under conditions of use and in which the separating head is movable with respect to the main body of the tool, thereby enabling the tool to be applied in the most effective way for separating the sheets and also enhancing the convenience of operation of the tool as a whole.

My invention further includes other objects and novel features of design, construction and arrangement hereinafter referred to more particularly or which will be apparent from the following description of a preferred embodiment of the invention as

illustrated in the accompanying drawing in which Fig. 1 is a top plan view of the tool; Fig. 2 a side elevation thereof; Fig. 3 an enlarged transverse section on line 3—3 in Fig. 1 looking in the direction of the arrows; Fig. 4 a fragmentary detail view, partially in section and partially in elevation; Fig. 5 a detail view showing one of the retaining springs and its associated parts removed from the tool, and Fig. 6 a fragmentary section on line 6—6 in Fig. 1 but on a slightly larger scale than said figure. The same symbols are used to designate the same parts in the different views.

Speaking generally, the tool comprises a fluid or electrically operated hammer which may be of any suitable type in operative combination with the separating head whereby there may be imparted to the latter a series of blows or impulses in rapid succession in such manner that when the edge of the head is disposed at the line of cleavage between two adhering sheets the head may be forced progressively forward between the sheets so as to separate them.

More specifically, the hammer, generally designated as H, may comprise the usual cylinder 1 enclosing a reciprocating plunger and valve mechanism (not shown), handle or grip 2, control valve 3 and nipple 4 for the reception of the end of the hose or wires by which the fluid or current for operating the hammer is conveyed thereto. As fluid operated hammers of this general character are well known and in common use additional description thereof would be superfluous, it being understood however that for the purposes of the present invention the hammer may be operated by fluid such as air or steam or even by electricity so long as it is capable of rapidly reciprocating its movable plunger so as to deliver a rapid sequence of blows in the well known manner.

At its forward end the hammer is provided with a socket adapted for the reception of the shank 5 at the rear end of a shaft 6 at the opposite or forward end of which is disposed the separating head 7.

This head, which is desirably formed of brass, bronze or other metal which while

relatively hard and durable is of a character which will not injure the sheets, is of somewhat peculiar shape having a front edge 8 which is fairly sharp and curved rearwardly 5 from its center in opposite directions toward the sides 9 and 10 of the head when the latter is viewed as in Fig. 1 and which extend rearwardly parallel to the axis of the shaft 6. From the edge 8 the upper and lower surfaces 10 faces or faces of the head, designated as 11 and 12, are curved outwardly and rearwardly in opposite directions, then extended parallel to each other and finally again curved oppositely inwardly until they meet. It will 15 thus be apparent that the front edge 8 of the head forms the apex of a fairly blunt wedge-shaped element having convex upper and lower faces in the rear of its leading edge so that as the head is progressively 20 moved between the adjacent sheets of the pack the sheets will be forced apart at a considerable angle, and further, by reason of the curvature of the faces of the head which contact with the surfaces of the sheets the 25 later will not be scratched or otherwise damaged as the head passes over them.

The head is secured to the shaft 6 so as to permit a limited oscillatory movement with respect thereto in a plane normal to the upper and lower faces of the head, and to this end the rear end of the head may be centrally cut out to provide a depression or slot 13 for the reception of the front end of the shaft which is correspondingly widened at 30 this point so as to lie snugly between the sides of the slot. As best shown in Fig. 6, the forward extremity 14 of the shaft is preferably formed on the arc of a circle whose center lies at the axis of the shaft and the bottom 15 of the slot formed on a similar radius of curvature, so that when the head and shaft are connected by means of a transversely extending pivot pin 16 which passes through the end of the shaft and adjacent 40 parts of the head and whose axis is between the said center and the end of the shaft; the head is capable of limited rotation or oscillation about the pivot while the abutting engagement of the shaft with the bottom of the slot effects a direct transference to the head of the blows or impulses delivered to the shank of the shaft and thus largely relieves the pivot pin of this duty. 45

For maintaining the shank 5 of the shaft 50 in the hammer socket and the shoulder 20 formed on the shaft at the base of the shank snugly against the end of the hammer, I provide yielding means, now to be described, and which comprise a pair of coil springs 21 and 22, which are preferably identical with each other, arranged on opposite sides of the hammer cylinder 1. At each end of each of these springs is disposed a cap 23 having a circular flange adapted to seat against the 55 end of the spring and a central cylindrical

part adapted to enter the spring for a short distance. Each cap is drilled longitudinally to provide a pair of parallel spaced holes in one of which is fixedly seated the extremity of a rod 24 which is extended through the 60 spring and freely through the corresponding hole in the cap at the other end thereof to project therebeyond. In like manner a corresponding rod 25 has one end fixedly seated in the opposite cap, that is, the cap 65 through which rod 24 freely extends, and is extended through the spring in the opposite direction and arranged to project beyond the other cap, that is, the cap in which the end of rod 24 is seated. The ends of the rods 70 may be secured in the respective caps in any suitable way, conveniently by driving the rod through one of the holes in the cap and then heading over the end of the former as shown, while the diameter of the other hole 75 in each cap through which the other rod is extended is made sufficiently great so that the rod is readily movable therein. It will thus be apparent that when the parts just described are assembled as shown in Fig. 5 the 80 spring may be compressed between the caps by pulling on the projecting ends of the rods in opposite directions, and to enable the attachment of the assembled device to the tool an eye is formed on the end of each rod 85 after the assembly is completed. It will be understood that the arrangement of the rods and caps is the same with respect to each of the springs 21 and 22 and that the latter are arranged on opposite sides of and parallel 90 to the hammer cylinder 1.

The eye at the end of each rod 24 disposed adjacent the grip 2 is connected to the latter or other convenient point by a strap or loop 95 26 of suitable shape to pass through the opening in the grip and over the front part thereof and through the eye; preferably each of these straps is made from a single length of rod which is first bent to approximately proper shape to form the strap and its ends then sprung apart so as to enable the strap to be passed through the eye of the rod and through the grip after which the ends are sprung back into position and welded together. This makes a strong and safe construction and prevents any chance of the ends of the strap being pulled apart as might be the case were they not solidly united. 105

The eye at the end of each of the forwardly extending rods 25 is secured to the shaft 110 6 preferably adjacent its rear end through the medium of a collar surrounding the shaft and comprising a pair of similar members 30 and 31 each having an arcuate central portion adapted to seat over the shaft and outwardly projecting ends drilled for the passage of bolts 32 which serve to clamp the members firmly about the shaft and also to receive the eyes at the ends of the rods as best shown in Fig. 3, and to prevent the col- 115 120 125 130

lar from slipping longitudinally on the shaft I preferably form in the latter at the point where the collar is to be attached an annular groove 33 and provide the central parts of the members of the collar with a corresponding ridge adapted to seat therein (see Fig. 4).

It will of course be understood that the length of the springs, rods and straps is such that when the parts are assembled and the collar secured in position on the shaft the springs will be under compression and thus constantly tend to pull the collar and in turn the shaft toward the hammer thereby keeping the shoulder 20 snugly against the end 15 of the latter and maintaining the shank of the shaft securely in position in the socket, and further, that the action of the springs in this connection will be constant irrespective of the vibrations set up in the tool when 20 the latter is in use. The means for maintaining the shaft in operative position in the hammer which I have just described constitute a distinct improvement in the art as it 25 has been found in practice that the vibrations set up in percussive tools of this general character rapidly loosen and render inoperative means such as set screws and the like hitherto generally employed for holding the parts in operatively assembled relation 30 whereas my improved holding means in spite of the said vibration maintain the desired connection between the hammer proper and the tool shaft at all times and under all conditions of operation and yet permit the tool 35 shaft to be readily removed or replaced when desired.

It is thought that the method of operating my improved tool will be apparent without extended description, the edge 8 of the separating head being merely placed against the line of cleavage at the ends or sides of a pair of adhering sheets and the hammer then operated so as to impart a series of impulses or blows to the end of the shank 5, the operator meanwhile pushing the tool forwardly so as to cause the head to enter between the sheets and force them apart. By reason of the hinge connection between the head and shaft it is possible to apply the tool to the sheets and to exert the requisite forward push on the former in the most effective way to bring about the desired separation of the sheets under the particular conditions of operation encountered and, as hitherto stated, 55 by reason of the peculiar conformation of the head and the fact that the faces thereof which come into contact with the surfaces of the sheets are curved and devoid of any projecting corners or angles the sheet surfaces are not scratched or marred during the passage of the head thereover while the sheets are rapidly and effectively forced apart.

While I have herein described a preferred form of my invention with considerable particularity I do not thereby desire or intend

to limit myself specifically thereto as, if desired, changes may be made in the design, construction and arrangement of the various parts to adapt the invention to different forms of hammers or for other reasons which 70 may make the same advisable without departing from the spirit and scope of the invention as defined in the appended claims.

Having thus described my invention, I claim and desire to protect by Letters Patent 75 of the United States:

1. In a tool of the class described, the combination of a fluid actuated hammer adapted to deliver a series of blows in rapid succession, a shaft, a head hingedly connected with one end of the shaft and comprising a relatively sharp free edge and oppositely outwardly curved opposed faces extending therefrom toward its point of connection to the shaft, and yielding means for operatively securing the other end of the shaft to the hammer. 80

2. In a tool of the class described, the combination of a fluid actuated hammer adapted to deliver a series of blows in rapid 90 succession, a shaft adapted to receive said blows at one end and having a head hingedly connected thereto at the other, said head comprising a relatively sharp free edge extending substantially normal to the axis of 95 the shaft and outwardly and oppositely convexed faces extending from said edge toward said shaft, and yielding means interposed between the shaft and the hammer 100 adapted to maintain the shaft in operative relation with the hammer and in a position to receive the blows delivered thereby.

3. In a tool of the class described, the combination of a fluid actuated hammer adapted to deliver a series of blows in rapid 105 succession, a shaft having at one end a shank seated in the hammer and adapted to receive said blows and a head pivoted adjacent one end to the opposite end of the shaft for oscillation with respect thereto about an axis normal to the axis of the shaft, said head being provided with oppositely outwardly curved faces merging into a single relatively sharp edge at the free end of the head, and means 110 for connecting the shaft to the hammer comprising a spring disposed parallel to the hammer, and relatively movable means connecting the ends of the spring respectively with the hammer and with the shaft and adapted to maintain said spring in a state of 115 compression to draw said shaft and hammer together. 120

4. In a tool of the class described, the combination of a fluid actuated hammer having a socket, a shaft having one end adapted to seat in said socket, means for maintaining the shaft in the socket, and a head at the opposite end of the shaft and hingedly secured thereto by a pivot pin extended transversely through the head and 125 130

through the shaft, the end of the shaft being in abutting engagement with the head, whereby the blows delivered by the hammer to the shaft are transmitted directly thereto through to the head.

5. In a tool of the class described, the combination of a fluid actuated hammer having a socket, a shaft having one end adapted to seat in said socket, means for 10 maintaining the shaft in the socket, a head at the opposite end of the shaft having a slot adapted to receive the adjacent end of the shaft, the end of the shaft and the bottom of the slot being formed on the same 15 radius of curvature and disposed in abutting engagement, and a pivot pin extended transversely through the head and the end of the shaft whereby said head is capable of limited oscillation about the pin with respect to 20 the shaft and the abutting relation of said surfaces constantly maintained throughout the extent of said movement of oscillation.

6. In a tool of the class described, the combination of a fluid actuated hammer 25 having a socket adjacent one end, a shaft having an end adapted to seat in said socket and means for yieldingly connecting the hammer and the shaft comprising a pair of coil springs disposed on opposite sides of 30 the hammer, a pair of parallel rods extended through each spring and projecting beyond the ends thereof in opposite directions, means for connecting one end of each rod with the adjacent end of the spring, and 35 means for connecting the other ends of the rods respectively with the hammer and with the shaft.

7. In a tool of the class described, the combination of a fluid actuated hammer having 40 a socket at one end and a grip at the other, a shaft having one end adapted to seat in said socket and an oscillatory wedge-shaped head at the other, and yielding means for maintaining the shaft in the socket and comprising a pair of coil springs disposed on opposite sides of the hammer in parallel relation, a pair of rods extended through each spring and projecting beyond the ends thereof in opposite directions, a cap at each end 45 of each spring, each cap forming a seat for the adjacent end of one of said rods and a guide for the other rod, means connecting the free ends of the rods adjacent the grip therewith, and means connecting the free 50 ends of the other rod with the shaft whereby said springs are maintained under compression and tend to pull said hammer and said shaft together.

8. In a tool of the class described, the combination of a fluid actuated hammer having 55 a socket, a shaft adapted to enter said socket, a removable collar mounted on the shaft, a pair of rods extending on opposite sides of the shaft from the collar toward the hammer, a coil spring surrounding each rod,

means for securing the end of each rod to that end of the adjacent coil spring remote from the collar, another pair of rods respectively extended through said springs, means for connecting the end of each of said rods 70 to that end of the adjacent spring next to the collar, and means for connecting the opposite end of each of said rods to the hammer.

9. In a tool of the class described, the combination of a fluid actuated hammer having 75 a grip at one end and a socket at the other, a shaft adapted to enter the socket and having a peripheral groove in its surface, a removable collar engaging said groove and clamped about the shaft and yielding means 80 for holding said shaft seated in said socket and comprising a pair of rods extending from said collar on opposite sides of the shaft toward the grip, a coil spring surrounding each rod, means for connecting the end of each rod to that end of the adjacent spring remote from the collar, another pair of rods respectively extending through the 85 springs and projecting therebeyond in the direction of the grip, means for securing the end of each rod to that end of the adjacent spring which is remote from the grip, and means connecting the other ends of each of said rods respectively with the grip to thereby maintain said springs under compression.

10. In a tool of the class described, a sheet separating head comprising a body having parallel sides and smooth faces extending therebetween from the front edge toward the 100 rear end of the head, said front edge being relatively sharp and said faces being outwardly and oppositely curved therefrom toward said rear end, and each face adjacent said edge being slightly sloped from its center toward the sides of the head.

11. In a tool of the class described, a shaft and a head disposed adjacent one end thereof and pivoted thereto for limited oscillation in a plane parallel to the axis of the 110 shaft, said head comprising parallel sides disposed normal to the axis of the pivot and oppositely convexed faces meeting in a relatively sharp edge remote from that end of the head which is pivoted to the shaft.

12. In a tool of the class described, a shaft having one of its ends conforming to an arc whose center lies in the axis of the shaft, a head having a slot adapted for the reception of the end of the shaft, the bottom of the slot conforming to the same curvature as the end of the shaft, and a pivot pin extending transversely through the head and end of the shaft and connecting the head and the shaft with said curved surfaces in abutting engagement, said head having curved upper and lower surfaces meeting in a relatively sharp edge at that end of the head remote from its point of connection with the shaft.

13. In a tool of the class described, the

combination of a fluid actuated hammer adapted to deliver a series of blows in rapid succession, a shaft, a head hingedly connected with one end of the shaft and comprising a relatively sharp free edge and oppositely outwardly divergent faces extending therefrom toward its point of connection to the

shaft, and yielding means for operatively securing the other end of the shaft to the hammer.

10

In witness whereof, I have hereunto set my hand this 22 day of June, 1926.

WILLIAM T. SCOTT.
